UNITED STATES PATENT OFFICE.

CARL TOBER, OF BERLIN-KARLSHORST, GERMANY.

BRAIDING MACHINE.

Application filed December 2, 1926, Serial No. 152,179, and in Germany December 8, 1925.

This invention relates to braiding machines with rows of bobbins rotating in opposite direction of which the inner bobbins are continuously driven by a roller system.

According to this invention, the rollers for driving the inner bobbins are provided circumferentially with one or more helical recesses, in which recesses the threads passing from the outer row of bobbins lie during their passage through the roller system. The threads therefore during such passage cannot pass between the "nip" of contacting rollers in the roller system whilst contact of the contacting rollers at the points of the recesses is maintained owing to the oblique position of the recesses relatively to the axis of the rollers so that in spite of the recesses the rollers of the roller system may drive without shock or thrust.

A further object of the invention is so to arrange the drive rollers for the inner bobbins and/or the slide rollers connected with the bobbin slides that the rotational planes of these rollers about their own axes are parallel or approximately so with their rotational planes about the braiding axis.

The advantage of this arrangement consists among others of avoiding a continuously varying position of the rotational plane of the roller arrangement such as obtains in the roller system herebefore employed, i. e. avoiding expenditure of power to overcome a top like action of the rollers (see for example the arrangement described in the German specification No. 415,642). It is known that a top like action (the quickly moving rollers of the roller system work as such) allows a directly forward movement in its own rotational plane, but causes very considerable resistance when in its forward movement, the direction of its rotational plane is varied continuously to a large extent, as is the case in the known roller arrangements, where at each rotation of the braiding machine, the rotational plane of each roller is given a sudden turn of about 360° so that the rotational planes of the rollers thus are subjected to a continuous and very quick alteration.

The invention is illustrated in the accompanying figures in which Figure 1 is a vertical section through a braiding machine in which for greater clearness two inner bobbins

only each with a drive roller and a slide roller are shown.

Figure 2 is a section on the line A—B; Figure 3 shows a drive roller to a larger scale.

Referring to Figure 1, 1 is a base plate carrying at its centre a bearing 17 on which rotates the hub of an outer bobbin carrier 7. 18 are outer bobbins cooperating with outer thread guides consisting of rollers 3 and a swing lever (not illustrated). Roller 3 rolls in known manner upon a stationary cam track 8 which is secured upon arms 44 on the base plate 1. The carrier 7 is also provided with a guide track 41 for a bobbin slide 37 and with a ring of teeth 33. The carrier 7, with the aforesaid parts, is given a circular movement about the braiding axis, by means of the bevel wheel 34 secured thereto, and in mesh with a bevel wheel 36 mounted upon a driving shaft 29.

The slides 37 which carry the inner bobbins 20 and rotate upon the guide track 41 in an opposite direction thereto are driven by a roller system in the following manner. The bevel wheel 36 is also in mesh with a bevel wheel 42 which because it is in mesh with the opposite diametral point of the bevel wheel 36, to that of the bevel wheel 34 is rotated in the opposite direction to the said bevel wheel 34 the bevel wheel 42 being secured on the hollow shaft 25 which is rotatably mounted in the main bearing 17. The upper end of the shaft 25 is connected with a roller carrier 26, bosses 26^a on which receive the axles 31 of drive rollers 30.

When the carrier 26 is rotated, drive rollers 30 act on slide rollers 23 connected by their spindles 22 to the slides 37 so that the slides 37 are moved in the direction of the arrow (see Figure 2) around the braiding axis.

In order to allow the outer threads, which have a to and fro movement in slots 40 of the carrier 7 relatively to the slide track 41, but relatively to the roller system 30, 23 a wave like movement σ , see Figure 2, to pass between the rollers 30 and the slide rollers 23, these rollers 30, 23 should be given, besides their circular movement about the braiding axis, a rotational movement about their own axes. This rotation of the rollers 30 is effected by securing to the spindles 31 of the drive rollers 30 toothed wheels 32 in

mesh with a ring of teeth 33 on carrier 7. The rotation thus imparted to the drive rollers 30 about their own axes is transferred to the slide rollers 23.

5. The direction of the drive of the carrier 7 and therefore of the ring of teeth 33 is shown by the dotted lines in Figure 2 as being in a clockwise direction. The toothed wheels 32 connected to the drive rollers 30 10 roll round the ring of teeth 33 and rotate the drive rollers 30 in a clockwise direction as shown by the arrow about their own axes. The plate 26, in which the spindles 31 of the drive rollers 30 are mounted, rotates 15 however in the direction of the arrow i. e. in the opposite direction to that of the carrier 7 whereby the rollers 30 are given, besides the rotation about their own axes, a movement of rotation about the braiding axis so that they move the slide rollers 23 20 (which as before set out have a movement of rotation about their own axes imparted thereto by the rollers 30) the slides 37, to which the spindles of the rollers 23 are connected, and the inner bobbins 20 carried thereby being also rotated around the braiding axis.

The necessary driving pressure between the rollers 30, 23, for effecting the rotation 30 of the rollers 23 about their own axes is obtained by virtue of the reaction therebetween owing to the force transmitted thereby from the plate 26 to the slides 37.

The drive rollers 30 are provided with 35 helical recesses 200 in which the thread lies when it passes between the drive rollers 30 and the slide rollers 23. This recess 200 is shown in the drive roller on the left in Figure 1 and in all driving rollers 30 in Figure 2, and also in the drive roller 30 shown to a larger scale in Figure 3.

The path described by the outer threads relatively to the roller system is diagrammatically indicated in Figure 2 by the thread 40 path *o*. The driving action between the drive and slide rollers 30, 23, is indicated by the arrows between the axes 31 and 22 of the drive and slide rollers. Each outer thread passes with a so-called 2 over 2 braid (see 45 thread path *o* in Figure 2) first beneath the slide roller 23, then between the contacting rollers 23 and 30, during which it lies in the recess 200 and then passes over the roller 30 and through an intermediate space *z* between 50 the non-co-operating faces of the rollers after which it passes below the neighbouring slide roller and again passes into a recess 200 in the line of contact of the drive roller 30 with its appertaining slide roller in order then to pass over the neighbouring two inner bobbins. Between non-co-operating 55 drive and slide rollers an intermediate space *z* is provided. When the machine is not in operation it may, however, happen 60 owing to the momentum of the slides that

the rollers 23 move out of contact with those drive rollers with which they had been contacting and move into engagement with the adjacent drive roller. In order that a thread now passing between these rollers 7 which are now contacting shall not be caught in the "nip" thereof the drive rollers 30 are provided with an additional helical recess 201 of opposite sense to that of 200 (Figure 7 201) the recess 201 thereby corresponding to the inclined position of the thread when it passes on the opposite side of the roller 30 (see Figure 1). Recess 201 also comes into use when the machine is running backwards.

The number of teeth for the toothed 80 wheels is, with the use of one recess 200 only in each drive roller, with for example, 8 inner bobbins, in the relation 1:8 to the number of teeth of the ring of teeth. However, with a greater number of recesses 200 85 in each drive roller any other gear ratio may be employed, the only condition being that a recess should be in a correct position for the outer thread to lie therein.

In Figure 1 another roller 162 is provided 90 which does not appertain to the roller system but is applied to the slides 37 in order to convert a part of the sliding friction of the slides 37 in their guide track 41 into rolling 95 friction. 107 and 151 are protective shields which serve to protect the outer threads from becoming attached to any portion of the inner bobbins and their thread tension members which are not illustrated.

It will be seen from Figure 3 that the line 100 of contact *c-d* of rollers 30 and 23 is at an angle relatively to the recess 200, so that the rollers in spite of the recesses 200 (201) can always roll upon one another without any disturbance caused by thrust which might otherwise be caused by the recesses.

The rotational planes of the drive and slide rollers in Figure 1 both lie in the same plane as that in which the rollers rotate 110 about the braiding axis.

What I claim is:—

1. In a braiding machine the combination 115 with inner and outer rows of bobbins moving in circular paths but in opposite directions of a roller system for moving the inner bobbins comprising drive rollers rotatable about their axes and about the braiding axis and rollers co-operating with said rollers and carried by the inner bobbin frame and a recess at the circumference of each drive roller adapted to receive the threads from the outer bobbins.

2. In a braiding machine the combination 120 with inner and outer rows of bobbins moving in circular paths but in opposite directions, of a roller system for moving the inner bobbins comprising drive rollers rotatable about their axes and about the braiding axis and rollers cooperating with 125 said rollers and carried by the inner bobbin

frame and a recess at the circumference of each drive roller situated at an angle other than a right angle to the axis thereof for receiving the threads from the outer bobbins.

5. 3. In a braiding machine the combination with inner and outer rows of bobbins moving in circular paths but in opposite directions, of a roller system for moving the inner bobbins comprising drive rollers rotatable about their axes and about the braiding axis and rollers cooperating with said rollers and carried by the inner bobbin frame and a helical recess at the circumference of each drive roller for receiving the threads from the outer bobbins.

4. In a braiding machine the combination with inner and outer rows of bobbins moving in circular paths but in opposite directions of a roller system for moving the inner bobbins comprising drive rollers rotatable about their axes and about the braiding axis the plane of rotation of said rollers about their own axes being parallel with their plane of rotation about the braiding axis and rollers cooperating with said rollers and carried by the inner bobbin frame and a recess at the circumference of each drive roller adapted to receive the threads from the outer bobbins.

5. In a braiding machine the combination with inner and outer rows of bobbins moving in circular paths but in opposite directions of a roller system for moving the inner bobbins comprising drive rollers rotatable about their axes and about the braiding axis the plane of rotation of said rollers about their own axes being parallel with their plane of rotation about the braiding axis and rollers cooperating with said rollers and carried by the inner bobbin frame and a recess at the circumference of each drive roller situated at an angle other than a right angle to the axis thereof for receiving the threads from the outer bobbins.

6. In a braiding machine the combination with inner and outer rows of bobbins moving in circular paths but in opposite directions of a roller system for moving the inner bobbins comprising drive rollers rotatable about their axes and about the braiding axis the plane of rotation of said rollers about their own axes being parallel with their plane of rotation about the braiding axis and rollers cooperating with said rollers and carried by the inner bobbin frame and a helical recess at the circumference of each drive roller for receiving the threads from the outer bobbins.

7. In a braiding machine the combination with inner and outer rows of bobbins moving in circular paths but in opposite directions of a roller system for moving the inner bobbins comprising drive rollers rotatable about their axes and about the braiding axis and rollers co-operating with said rollers and

carried by the inner bobbin frame and a pair of recesses at the circumference of each drive roller and on opposite sides thereof adapted to receive the threads from the outer bobbins.

8. In a braiding machine the combination with inner and outer rows of bobbins moving in circular paths but in opposite directions of a roller system for moving the inner bobbins comprising drive rollers rotatable about their axes and about the braiding axis and rollers co-operating with said rollers and carried by the inner bobbin frame and a pair of recesses each on opposite sides of the circumference of each drive roller at an angle other than a right angle to the axis thereof for receiving the threads from the outer bobbins.

9. In a braiding machine the combination with inner and outer rows of bobbins moving in circular paths but in opposite directions of a roller system for moving the inner bobbins comprising drive rollers rotatable about their axes and about the braiding axis and rollers cooperating with said rollers and carried by the inner bobbin frame, and a pair of helical recesses at the circumference of each drive roller and on opposite sides thereof for receiving the threads from the outer bobbins.

10. In a braiding machine the combination with inner and outer rows of bobbins moving in circular paths but in opposite directions of a roller system for moving the inner bobbins comprising drive rollers rotatable about their axes and about the braiding axis the plane of rotation of said rollers about their own axes being parallel with their plane of rotation about the braiding axis and rollers cooperating with said rollers and carried by the inner bobbin frame, and a pair of recesses at the circumference of each drive roller and at opposite sides thereof and adapted to receive the threads from the outer bobbins.

11. In a braiding machine the combination with inner and outer rows of bobbins moving in circular paths but in opposite directions of a roller system for moving the inner bobbins comprising drive rollers rotatable about their axes and about the braiding axis the plane of rotation of said rollers about their own axes being parallel with their plane of rotation about the braiding axis and rollers cooperating with said rollers and carried by the inner bobbin frame, and a pair of recesses at the circumference of each drive roller at opposite sides thereof and at an angle other than a right angle to the axis of said drive roller and adapted to receive the threads from the outer bobbins.

12. In a braiding machine the combination with inner and outer rows of bobbins moving in circular paths but in opposite directions of a roller system for moving the

inner bobbins comprising drive rollers rotatable about their axes and about the braiding axis the plane of rotation of said rollers about their own axes being parallel with 5 their plane of rotation about the braiding axis and rollers cooperating with said rollers and carried by the inner bobbin frame, and a pair of helical recesses at the circumference of each drive roller and at opposite sides 10 thereof and adapted to receive the threads from the outer bobbins.

13. In a braiding machine, the combination with inner and outer rows of bobbins moving in circular paths but in opposite 15 directions of a roller system for moving said inner bobbins comprising drive rollers rotatable about their own axes and about the braiding axis, and rollers cooperating with said drive rollers and carried by the 20 inner bobbin frame, the planes of rotation of said drive rollers and the rollers cooperating therewith about their own axes being parallel with their planes of rotation about the braiding axis, and a recess in the circumference 25 of each drive roller adapted to receive the threads from the outer bobbins.

14. In a braiding machine, the combination with inner and outer rows of bobbins moving in circular paths but in opposite 30 directions of a roller system for moving said inner bobbins comprising drive rollers rotatable about their own axes and about the braiding axis, and rollers cooperating with 35 said drive rollers and carried by the inner bobbin frame, the planes of rotation of said drive rollers and the rollers cooperating therewith about their own axes being parallel with the planes of rotation about the braiding axis, and a recess at the circumference 40 of each drive roller at an angle other than a right angle to the axis thereof for receiving the threads from the outer bobbins.

15. In a braiding machine, the combination with inner and outer rows of bobbins moving in circular paths but in opposite 45 directions of a roller system for moving said inner bobbins comprising drive rollers rotatable about their own axes and about the braiding axis and rollers cooperating with 50 said drive rollers and carried by the inner bobbin frame, the planes of rotation of said drive rollers and the rollers cooperating therewith about their own axes being parallel with their planes of rotation about the braiding axis, and a helical recess at the circumference 55 of each drive roller and at opposite sides thereof for receiving the threads from the outer bobbins.

cumference of each drive roller for receiving the threads from the outer bobbins.

16. In a braiding machine, the combination with inner and outer rows of bobbins moving in circular paths but in opposite 60 directions of a roller system for moving said inner bobbins comprising drive rollers rotatable about their own axes and about the braiding axis, and rollers cooperating with said drive rollers and carried by the 65 inner bobbin frame, the planes of rotation of said drive rollers and the rollers cooperating therewith about their own axes being parallel with their planes of rotation about the braiding axis, and a pair of recesses at the circumference of each drive 70 roller and on opposite sides thereof adapted to receive the threads from the outer bobbins.

17. In a braiding machine, the combination with inner and outer rows of bobbins 75 moving in circular paths but in opposite directions of a roller system for moving said inner bobbins comprising drive rollers rotatable about their own axes and about the braiding axis, and rollers cooperating with 80 said drive rollers and carried by the inner bobbin frame, the planes of rotation of said drive rollers and the rollers cooperating therewith about their own axes being parallel with their planes of rotation about the 85 braiding axis, and a pair of recesses each on the opposite sides of the circumference of each drive roller at an angle other than a right angle to the axis thereof for receiving the threads from the outer bobbins. 90

18. In a braiding machine, the combination with inner and outer rows of bobbins moving in circular paths but in opposite 95 directions of a roller system for moving said inner bobbins comprising drive rollers rotatable about their own axes and about the braiding axis, and rollers cooperating with said drive rollers and carried by the inner bobbin frame, the planes of rotation of said drive rollers and the rollers cooperating 100 therewith about their own axes being parallel with their planes of rotation about the braiding axis, and a pair of helical recesses at the circumference of each drive roller and on opposite sides thereof for receiving the 105 threads from the outer bobbins.

In testimony that I claim the foregoing as my invention I have signed my name this 22nd day of November, 1926.

CARL TOBER.
